UTILITY CART FOR GOLF BAGS AND SIMILAR ARTICLES

William D. Jones, E. Club Drive, Thomasville, Ga.

Filed Nov. 2, 1964, Ser. No. 82,428

Term of patent 14 years

(Cl. D14—3)

FIG. 1

FIG. 2

FIG. 3

FIG. 4

I claim:

The ornamental design for a utility cart for golf bags and similar articles, as shown.
